CLAIM

We claim the ornamental design for a LED mounting adapter, as shown and described.

DESCRIPTION

FIG. 1 is an isometric view of a first embodiment of an LED mounting adapter showing my new design;

FIG. 2 is a front elevation thereof;

FIG. 3 is a left side elevation thereof;

FIG. 4 is a top plan view thereof;

FIG. 5 is a bottom plan view thereof; and,

FIG. 6 shows the first embodiment in the environment in which it is used.

Broken lines illustrate the environmental structure in the drawing and are not part of the design sought to be patented.
